UNITED STATES PATENT OFFICE.

HENRY K. GILBERT, OF CHICAGO, ILLINOIS.

BRAKE-SHOE.

No. 806,252.

Specification of Letters Patent.

Patented Dec. 5, 1905.

Application filed January 16, 1905. Serial No. 241,362.

To all whom it may concern:

Be it known that I, HENRY K. GILBERT, a citizen of the United States, residing at Chicago, in the county of Cook and State of Illinois, have invented certain new and useful Improvements in Brake-Shoes, of which the following is a specification.

This invention refers to a means for strengthening the body of a brake-shoe by an integral truss of tough and ductile metal, usually wrought iron or steel, extending from the rear face of the shoe but connected rigidly with said shoe at its opposite ends.

The invention also refers to a means for anchoring said truss in said brake-shoe.

The invention further refers to a means for providing inserts of a metal having a different degree of hardness from that of the body of the shoe, which inserts are placed in the wearing-face of the shoe and may serve both to anchor said truss and to increase the coefficient of friction of said shoe.

The invention further refers to means for strengthening the securing-loop of brake-shoes and to the combination of said strengthening means with the truss hereinbefore mentioned.

In the accompanying drawings, Figure 1 is a perspective view illustrating one embodiment of the truss of this invention formed for a brake-shoe. Fig. 2 illustrates said truss with anchor-blocks secured upon its opposite ends. Fig. 3 is a side elevation of one form of brake-shoe embodying my invention, partly in section, illustrating the position of the anchor-blocks in the body of the shoe and also the position of the truss. Fig. 4 is a rear face view of said brake-shoe, a portion of the attaching-loop being in section. Fig. 5 illustrates a form of truss, the truss-bars of which have inwardly-extending projections adapted to be embedded within the top of the securing-loop for strengthening said loop. Fig. 6 is a side elevation, partly in section, of a shoe provided with the truss shown in the last preceding figure. Fig. 7 is a transverse view through the securing-loop of a brake-shoe, showing a modification of the strengthening means for said securing-loop. Fig. 8 is a perspective view of said modified strengthening means separate from the shoe-body.

In the construction of a brake-shoe embodying this invention I provide a truss composed of one or more pieces of metal, preferably wrought iron or steel and in this instance of rod form.

1 refers to the form of truss shown in Fig. 1. The rod or rods which constitute said truss 1 are bent in arch form to provide the truss-bars 2 and 3, which truss-bars at their ends have feet portions 4 and inturned connecting-bars 5, as shown in Figs. 2 and 3. Anchor-blocks 6, formed of wrought-iron, cast-steel, or other suitable metal of different texture and hardness from the metal of the body 65 of the shoe, may be placed between the feet portions 4 of the truss-bars and the connecting-bars 5 firmly embedded within said anchor-blocks. In practice said bars are so embedded by forging the anchor-blocks hot 70 over said connecting-bars or placing said bars in the mold in which said anchor-blocks are cast and pouring molten steel or other metal into said molds. The anchor-blocks 6, the feet 5, and the ends of the truss-bars 2 75 and 3 are similarly embedded within the body 7 of the shoe—that is to say, said blocks, feet, and portions of said truss-bars are placed within the mold in which the shoe-body is cast and molten metal poured into said mold 80 surrounding said anchor-blocks and bars. If desired, the use of anchor-blocks may be dispensed with, as shown in Fig. 6. The middle portions of the truss-bars 2 and 3 extend through the side portions of the attaching-loop 8, which loop is formed of the same material and integral with the body portion of the shoe. The loop 8 thus forms a strut for the truss-bars and, embedding them, as it does, and thus holding them rigidly, stiffens the 90 shoe.

In Fig. 5 I have illustrated another form of truss, (designated as 1^a), the truss-bars of which are provided with projections 1^b, adapted to be embedded in the upper side of the securing-loop 8^a of the brake-shoe, as shown in Fig. 6, to strengthen said loop. The projections mentioned have been formed in this instance by suitably bending the rod of which the truss is made and flattening the bent portions.

A different means for strengthening the securing-loop of a brake-shoe is illustrated in Figs. 7 and 8. A rectangular sheet-metal loop 9 of oblong cross-section, having two 105 ears 10 punched from the material of which the loop is formed and extending outwardly from each side of the upper end of said loop, is adapted to be embedded during the casting process in the top and side walls of the 110 securing-loop 8^b and in the adjacent part of the shoe-body, the truss-bars 2^a passing over

and bearing upon the ears 10. The loop 9 binds the parts of the securing-loop 8^b together and anchors it firmly to the shoe-body.

The shoe is secured to the brake-head (not shown) in any suitable manner, as by means of the attaching-loop 8 8^a 8^b, the ends of the brake-head or portions thereof bearing against shoulders 11, formed upon the rear face of and at opposite ends of the shoe-body 7.

10. Great strength is imparted to the body of the shoe by the truss 1, and should said shoe become cracked or broken between its ends the parts of the shoe will be retained in position and will be nearly if not quite as serviceable as a perfect shoe. The anchor-blocks 6 set in the face of the shoe being of softer metal than said shoe increase its braking efficiency by raising its coefficient of friction.

15. The embodiment herein shown of this invention may be modified in various ways without departing from the spirit and scope of the invention, wherefore I desire to have it understood that I do not wish to limit myself to the particular details herein set forth.

20. 25. I claim as my invention—

1. A brake-shoe having an integral truss formed of a malleable-metal rod bent to form said truss the end portions only of said truss being embedded in said shoe.

30. 2. A brake-shoe having secured thereto a truss comprising two truss-bars, the end portions only of said bars being embedded in said shoe.

35. 3. A brake-shoe having an integral truss made of a rod bent to form two truss-bars.

40. 4. A brake-shoe provided with a securing-loop and an integral truss of malleable metal, the middle portions of said truss being embedded within said securing-loop, and the end portions only of said truss being embedded in the brake-shoe.

45. 5. A brake-shoe provided with a securing-loop, also having secured thereto a truss comprising two truss-bars, the middle portions of said truss-bars being embedded in said securing-loop, and the end portions only of said bars being embedded in the shoe-body.

6. A brake-shoe having a securing-loop integral with said shoe and an integral truss comprising two truss-bars, which truss-bars extend through the sides of said loop, the end portions only of said bars being embedded in the shoe-body.

7. A brake-shoe having an integral truss formed of a malleable-metal rod bent to form said truss, said shoe having anchor-blocks embedded in it for said truss.

8. A brake-shoe having a truss formed of two curved truss-bars, the ends of said truss-bars being bent to form feet portions, which feet portions are secured to anchor-blocks embedded in the body of the shoe.

9. A brake-shoe having an integral truss made of a rod bent to form two truss-bars, the ends of said truss-bars being embedded in anchor-blocks, which anchor-blocks are embedded in the body of the shoe.

10. A brake-shoe having an integral truss formed of malleable metal, said shoe having anchor-blocks embedded in it for said truss, one side of each of said blocks being flush with the face of the shoe.

11. A brake-shoe having an integral truss made of a rod bent to form two truss-bars, said shoe having an integral securing-loop through the sides of which loop the truss-bars of said truss extend, said shoe having embedded in its face two anchor-blocks in which the ends of said bars are embedded.

12. A brake-shoe having a truss secured to the body of the shoe, said shoe having a securing-loop through which the middle portion of said truss extends, said truss having a projection thereon lying within said loop.

13. A brake-shoe having secured thereto a truss comprising two truss-bars, said shoe having a securing-loop through which said truss-bars extend, said truss-bars being bent within said loop to provide strengthening projections.

HENRY K. GILBERT
